UNITED STATES PATENT OFFICE.

MARTIN L. SENDERLING, OF JERSEY CITY, NEW JERSEY.

DESIGN FOR A FIFTH-WHEEL FOR VEHICLES.

SPECIFICATION forming part of Design No. 33,518, dated November 6, 1900.

Application filed October 28, 1899. Serial No. 735,131. Term of patent 14 years.

To all whom it may concern:

Be it known that I, MARTIN L. SENDERLING, a citizen of the United States, and a resident of Jersey City, in the county of Hudson and State of New Jersey, have invented and produced a new and original Design for a Fifth-Wheel for Vehicles, of which the following is a specification.

The essential feature of my design consists in a fifth-wheel for vehicles, presenting in top plan a circle cut by a Latin cross and in side elevation an irregular T, surmounted by a disk having an arched top.

In the accompanying drawings, Figure 1 represents a top plan view of the fifth-wheel, and Fig. 2 is a view of the same in side elevation.

The upright of the cross is denoted by A, the horizontal by B, and the circle by C. The upright is shown as bifurcated at one end, 20 presenting the branches *a* and *a'*, and is narrowed at the opposite end. The arched top of the disk or circle C is denoted by *c*.

What I claim is—

The design for a fifth-wheel, substantially 25 as herein shown and described.

In testimony that I claim the foregoing as my invention I have signed my name, in presence of two witnesses, this 24th day of October, 1899.

MARTIN L. SENDERLING.

Witnesses:

FREDK. HAYNES,
EDWARD VIESER.
